UNITED STATES PATENT OFFICE.

THOMAS ELLIOTT, OF CINCINNATI, OHIO, ASSIGNOR TO THE CINCINNATI CAR COMPANY, OF CINCINNATI, OHIO, A CORPORATION OF OHIO.

RAILWAY CAR.

Application filed April 17, 1922. Serial No. 553,653.

To all whom it may concern:

Be it known that I, THOMAS ELLIOTT, a citizen of the United States, residing at Cincinnati, in the county of Hamilton and State of Ohio, have invented certain new and useful Improvements in Railway Cars, of which the following is a specification, reference being had therein to the accompanying drawing.

10 This invention relates to railway cars, designed particularly for use in city and interurban passenger traffic.

The major object of my invention is to materially lighten the car so as to reduce 15 the cost of production and therefore the selling price, and to decrease the cost of operating the car over the tracks of the line, without lessening the essential strength and without reducing the seating capacity as 20 compared with existing standard cars.

The weight of the car is lessened most largely by the following features of improvement:—

(a) The elimination of all but two of the 25 usual series of combined posts and rafters, known as U-posts, and the substitution of half posts located intermediate of the retained U-posts and extending from the eaves to the belt rail.

30 (b) The combination of curved side plates with these half posts, such plates extending from the belt rail to the corner sill and their curvature permitting of making them thinner and yet adding strength and a bracing effect, which thereby enables the use of such half posts instead of full posts extending from the eaves to the side sill.

(c) The use of a continuous belt rail from the door post at one end of the car to the 40 door post at the other end, such curved side plates and such half posts aiding in permitting the belt rail to be so continuous.

(d) The combination of essentially vertical channel posts and the belt rail extended 45 laterally beyond such posts, with the side plate and the pier plate both inclined outward, the side plate from the sill and the pier plate from the eaves, to connect with the outer part of the belt rail, thus forming 50 a light but very strong bracing effect in the side wall of the car structure.

Another object of my invention is carried out by making the half posts in two parts, one part constituting the post proper 55 and the other part a fixed section secured

to the roof or upper structure, so that in case of breakage of the posts, as in collisions or accidents, they can be readily removed and new ones substituted without disturbing the permanent connection of the 60 upper section.

And a further object of my invention is that of giving to the belt rail the maximum of rigidity against lateral or up and down bending or springing by forming it with 65 an upper portion and inner and outer essentially vertical portions in the nature of flanges.

These and other objects I carry into successful effect by the above features, as will 70 more fully appear in the detail description now about to be given.

In the accompanying drawings:—

Fig. 1 is a side elevation of a railway car embodying my invention; 75

Fig. 2 is a detail partial plan view and horizontal section on the line 2—2 of Fig. 1, looking in the direction of the arrow and showing the essentially vertical channel posts, the top of the belt rail and the pier 80 plate with its ends carried into certain posts;

Fig. 3 is a transverse sectional view of the car structure taken on the line 3—3 of Fig. 1 and looking in the direction of the arrow; 85

Fig. 4 is a vertical sectional view and elevation, on an enlarged scale, of a part of the roof structure, the belt rail and a half post, taken on the line 4—4 of Fig. 1 and looking in the direction of the arrow; 90

Fig. 5 is an enlarged sectional view and elevation of the parts illustrated in the lower end of Fig. 4;

Fig. 6 is a vertical longitudinal sectional view showing an end post, part of the side 95 sill and the end of a bolster;

Fig. 7 is an enlarged detail in transverse vertical section showing the side sill, curved side plate and part of a U-post;

Fig. 8 is an enlarged side elevation of a 100 portion of a car showing the same in skeleton form;

Fig. 9 is a horizontal sectional view of what is shown in Fig. 8, taken on the line 9—9 of Fig. 8 and looking in the direction 105 of the arrow;

Fig. 10 is an enlarged perspective view of the step, the gusset plate and adjacent beam members;

Fig. 11 is an enlarged detail view of a 110

portion of the side sill, a cross sill, an angle beam and the gusset plate;

Fig. 12 is a view taken on the line 12—12 of Fig. 8.

Fig. 13 is a similar view taken on the line 13—13 of Fig. 8; and

Fig. 14 is a transverse vertical sectional view taken on the line 14—14 of Fig. 8.

Referring to Fig. 1, I have illustrated a conventional type of steel city railway or interurban car in so far as concerns the general appearance and style. In this car I have embodied my invention. The structure consists of end sills 1, preferably channel shaped

in cross section, which are united to side sills 2 in the manner shown in Figs. 8, 9 and 10, through longitudinal beams 1^a, transverse beam 1^b and a gusset plate 1^c. This gusset plate is secured by bolts or rivets 1^d to the side sill 2 and by other bolts or rivets 1^e to the longitudinal beams 1^a, and to the end sill 1 by the fastenings 1^f, as shown particularly in Fig. 8.

A deck plate 2^a is riveted, as particularly shown in Fig. 9, to the end sill 1 and the longitudinal beams 1^a to further unite these parts.

The side sills 2 are angle shaped and extend through the length of the car from the door posts 4, as seen in Figs. 8 and 9. These door posts 4 are secured to the floor, as seen in Fig. 6, by angle brackets 5 and rivets 6 and 7.

U-posts 8 are secured to the side sills by rivets 9 extending through base flanges 10 of the posts and the sill, as seen best in Fig. 7.

Thus there are, in the car illustrated, two of these door posts 4 and intermediate of them two of these U-posts. The latter, as seen in Fig. 3, are formed of the two post members 8 and the arch member 8^a, preferably integral with the post members. The arch member 8^a forms a rafter. These two members are substantially the shape of the letter "U" inverted and hence these parts are called U-posts.

At each side of the car there is a belt rail 11 which extends from one door post 4 to the other and is secured to such post, as shown at 4^a in detail in Fig. 11.

At intervals between the two U-posts I place at either side of the car, stub posts 12 which rest on the side sill at their lower ends and at their upper ends fit under the belt rail presently to be described.

Overlying these door posts 4, U-posts 8, and stub posts 12 are the side plates 13 which are riveted along their lower margins to the outer flange of the side sills 2 by rivets 14, to the U-posts 8 by rivets 14^a, as seen in Figs. 1 and 3, and along their upper margins are secured to the outer flange of the belt rail by rivets 15, as seen in Figs. 1 and 3. And these side plates 13 are also secured to the stub posts 12, as seen in Fig. 1.

Thus, it will be seen that the lower part of the car structure is made very light and yet very strong, while, as will now appear, the upper part of the structure at each side is likewise made firm and rigid though light. 70 This is done by means of dividing the distance between the two U-posts 8 on each side of the window space with intermediate half posts 16, preferably made of wood, which, as seen more clearly in Fig. 4, extend from the roof structure down to and rest upon the belt rail 17, to which the half posts are anchored by bolts 18 buried in the posts and extended through the rail and held by nuts 19. 80

The belt rail is channel shape and constructed of steel and extends from the door post 4 at one end of the car to the door post 4 at the other end, with its outer flange secured, as by rivets 15, to the side plate 13 85 so as to partake of the vertical rigidity of such plate and so as to afford such plate lateral rigidity by reason of the channel shape form in cross section of this belt rail. And further rigidity is afforded by the anchored 90 connection between the half posts 16 and the belt rail, while the upper ends of the half posts are secured to the rafters 20, according to the position of the several half posts. The upper portions of these posts are divided 95 into two members, the lower member being composed of the half posts proper 16 and the upper of blocks 16^a, shoulders 17^a being formed between the parts to properly sustain the weight of the roof, while the posts 100 are secured by bolts 17^b to the sign board 17^c and the blocks are secured to the posts by bolts 17^d and to the rafters as well as the sign board 17^c through a bolt 17^e, all clearly shown in Fig. 4. 105

Thus, the half posts are made in sections detachably connected together, so that the half posts proper can be removed if broken or injured by an accident or for other cause, and new half posts be readily substituted 110 without disturbing the permanent or block section which is intimately worked into the roof and rafter construction.

Secured to each U-post and to the neighboring rafters 20, near each end of the car, is a channel iron 21 to stiffen the structure and interconnect these rafters. It will be seen that there is one of these channel irons near each end of the car. 115

A pier plate 22 is secured near its upper margin to this channel iron, and carried down at an incline to the outer flange of the belt rail 17, as by rivets 15. There is one of these pier plates just to the rear of each door and over the side plate 13. By observing Fig. 3 it will be seen that the pier plate and the side plate both incline inward from their point of connection with the belt rail and thus constitute braces as well as afford an ornamental exterior out- 120 125 130

line of the body. And it will be seen from Fig. 4 that the half posts 16 are so positioned that they conform in angular position to that of the pier plates and thus 5 continue the sloping sides or outline of the body from pier plate to pier plate, and give a bracing effect to the structure.

It will further be seen from Fig. 2, that 10 the pier plates have their side portions 24 bent inward and carried to the door post 4 and the U-posts 8 to which they are respectively secured by rivets 25. These in-turned portions 24 are above the belt rail, as shown by the dotted line 23 in Fig. 3, 15 so that the belt rail does not interfere with this extension of the sides of the pier plate to these posts. This arrangement further adds strength and rigidity to the structure, while these posts afford an excellent means 20 for securing the sides of the pier plates in addition to the connection of the top and bottom margins of such plates to the channel iron 21 and belt rail, as clearly seen in Fig. 3.

25 Bolsters 26 preferably in the form of boxes made of plate steel are provided with flanges 27 and capped with top plates 28 and secured to the top flanges of the side sills 2 by rivets 7 and other rivets 7^a. Each 30 car has two of these bolsters. This formation and manner of connection of the bolsters add another element of strength to the structure as the bolsters thus form beams which interconnect the opposite sides of the 35 car at the points where the bolsters are located.

It will be observed that the half posts 16 are grooved, as shown at 29 and 30 in Fig. 4, to form ways for the sashes indicated at 31 and 32. It will be seen also 40 that the heel of the half posts is cut away at 33 for the insertion of a window sill or stool 34 which lies upon the belt rail and is held by the passage therethrough of the anchor bolt 18, all as clearly shown in Fig. 5.

The pier plates have windows with fixed 45 glass sashes 35. Sliding doors 36 are arranged on both sides of the car and near each end, as shown, but I include herein no description of them and the manner of 50 their mounting, as that forms the subject matter of another application, Serial Number 553,654, filed April 17, 1922.

55 And the ends of the car are fashioned into the usual or any approved style of vestibule 37 with windows 38—features which are not a part of this invention.

It will now be seen that by reason of the 60 door posts 4 and the limited number or pairs of U-posts, with the intervening half posts combined with the long belt rails, I have provided a light but strong and durable frame structure. Then to these features it will be noted that I have added 65 and combined therewith the side plates

which tie together the side sills and the belt rails and which by their inclined position also afford a lateral bracing effect, with the further effective feature of the pier plates which tie together the belt rail and 70 the upper structure, and that I incline these pier plates from the outer margins of the belt rail inward to the upper structure to derive from them a further lateral bracing effect cooperating with that of the side 75 plates.

And it will further be observed, particularly from Fig. 2, that I connect the pier plates not only with the belt rail, but through bent-in side portions with the door 80 post and U-post and so tie together the belt rail and these posts through the instrumentality of the margins of the pier plate.

It will further be observed that I effectively unite the half posts with the belt rail and with the upper or roof structure, and that these half posts are inclined as in the case of the pier plate with the double result of utilizing these half posts to tie 85 together the belt rail and the roof structure, as also to obtain lateral bracing effects through the inclined positions of these posts. And to this I add the feature of the 90 removability of that part of these half posts which is most likely to be injured or broken in case of accident or collision so that new posts can be installed without 95 tearing loose that part of the posts which forms a permanent connection with the 100 roof structure.

Added to these several features is that of the effectiveness of the bolsters in laterally tying together the side sills at points in the length of the car where such interconnection of the side sills is important. 105

Having thus fully described my invention, what I claim as new and desire to secure by Letters Patent, is:—

1. In a car, the combination with a belt rail and posts inward thereof, of a pier plate secured to the belt rail and having its side margins extended inward and secured to said posts. 110

2. In a car, the combination, with a belt rail and a roof structure, of a half post formed in two parts, one part anchored to the belt rail and the other secured to the roof structure, and means for detachably connecting the two post parts together. 115

3. In a car, the combination with a belt rail and a roof structure, such rail occupying a position laterally beyond the roof structure, of a half post made in two sections, the longer section fitted upon and secured to the rail and inclining inward and the shorter section secured permanently to the roof structure, and a detachable connection between the two post parts. 125

4. In a car, the combination with a side 130

sill, a transverse beam and a beam extending forwardly thereof, of a gusset plate comprising a sheet of metal bent to fit against said several members and connected 5 therewith.

5. In a car, the combination with a side sill, a transverse beam and a longitudinal beam extending therefrom, of a gusset plate comprising a sheet of metal formed to fit 10 against said members, secured thereto, and a step carried by said gusset plate.

6. In a car, a frame, including side sills, door posts extending upward from said sills, U-posts extending upward from said 15 sills intermediate the door posts, a belt rail connecting the door posts and U-posts and spaced above said sills, longitudinal members each connecting a respective U-post and a respective door post and positioned 20 above the level of the belt rails, short posts connecting said sills and belt rails, half posts connecting the longitudinal members and belt rails between the U-posts and corner posts, and roof members supported at 25 their ends on said longitudinal members.

7. In a car, a frame, including side sills, door posts extending upward from said sills, U-posts extending upward from said 30 sills intermediate the door posts, a belt rail connecting the door posts and U-posts and spaced above said sills, longitudinal members each connecting a respective U-post and a respective door post and positioned above the level of the belt rails, short posts

connecting said sills and belt rails, half 35 posts connecting the longitudinal members and belt rails between the U-posts and corner posts, roof members supported at their ends on said longitudinal members, said belt rails being positioned outwardly 40 with respect to the side sills and the half posts and short posts being inclined to meet said belt rails.

8. In a car, a frame, including side sills, door posts extending upward from said 45 sills, U-posts extending upward from said sills intermediate the door posts, a belt rail connecting the door posts and U-posts and spaced above said sills, longitudinal members each connecting a respective U-post 50 and a respective door post and positioned above the level of the belt rails, short posts connecting said sills and belt rails, half posts connecting the longitudinal members and belt rails between the U-posts and 55 corner posts, roof members supported at their ends on said longitudinal members, said belt rails being positioned outwardly with respect to the side sills and the half posts and short posts being inclined to meet 60 said belt rails, inclined side plates secured to said sills and belt rails, and inclined pier plates secured to said belt rails and longitudinal members.

In testimony whereof, I affix my signature.

THOMAS ELLIOTT.
